UNITED STATES PATENT OFFICE.

LÁZÁR LUKÁCS, OF NEW YORK, N. Y.

AEROPLANE.

1,168,658.

Specification of Letters Patent. Patented Jan. 18, 1916.

Application filed April 6, 1914. Serial No. 829,899.

To all whom it may concern:

Be it known that I, LÁZÁR LUKÁCS, a subject of the King of Hungary, and resident of the city of New York, in the county of New York and State of New York, have invented certain new and useful Improvements in Aeroplanes, of which the following is a specification.

The present invention relates to aeroplanes, and has for one of its objects to generally improve and simplify the construction of the same.

Another object of the invention is to so arrange the propelling mechanism of the aeroplane that it offers the least resistance to the air, whereby the speed of the aeroplane is greatly increased compared with those heretofore in use, taking into consideration a given engine and a given number of revolutions of the same.

Another object of the invention is to produce a propelling mechanism which serves at the same time as the steering means of the aerial vessel.

With these and other objects in view, which will more fully appear as the nature of the invention is better understood, the same consists in the combination, arrangement and construction of parts hereinafter fully described, pointed out in the appended claims and illustrated in the accompanying drawings, it being understood that many changes may be made in the size and proportion of the several parts and details of construction within the scope of the appended claims without departing from the spirit or sacrificing any of the advantages of the invention.

One of the many possible embodiments of the invention is illustrated in the accompanying drawings, in which:—

Figure 1 is a front elevation of an aerial vessel constructed in accordance with the present invention; Fig. 2 is a side elevation of the same; Fig. 3 is a plan view thereof with the glider frames removed in order to more clearly show the construction of the device; and Fig. 4 is a plan view of a detail of construction.

In the drawings, the numeral 10 designates the frame of the vessel, made of a suitable light and rigid material and mounted upon wheels 11, which facilitate the transportation of the vessel and aid in the

ascent of the same. These wheels are made in the form of pulleys, over which run endless ropes 12, thereby providing sled-runner-like structures, which effectively prevent the tilting of the vessel when it runs over an uneven ground, etc. The frame is made in the form of a cage, and to its top are attached the glider frames of the machine, comprising superposed frames 13 and 14 of light and rigid material, which are provided with coverings of any suitable material, thereby forming aeroplanes. The glider frames are properly strengthened by stay-wires 15, to give them the required rigidity. Obviously any suitable number of glider frames may be used according to the requirements.

For actuating the propelling means of the vessel, a suitable source of power is provided, for instance an internal combustion engine 16, diagrammatically shown in the drawings. This engine is mounted upon a horizontally disposed lattice-work 17, its crankshaft 18 being arranged horizontally and transversely of the frame of the structure, that is to say parallel to the axle 19 of the front wheels 11. On each end of the crankshaft is mounted a screw propeller 20 of the required size and pitch, the planes of rotation of these propellers being parallel to the sides 21, 21 of the vessel frame. In rear of each propeller is mounted upon the shaft 18 a disk 22, said disks serving as fly-wheels, also as lateral balancing means, and furthermore a purpose which will be hereinafter described. With each propeller coöperate a plurality of vertically disposed planes 23, each comprising an oblong frame 24, that is covered with suitable material and pivotally mounted in horizontal longitudinal bars 25, which are attached in any suitable manner to and extend parallel to the sides of the frame of the vessel.

In the case shown in the drawings there are on each side of the vessel provided four frames 24, but it will be easily seen that their number may be varied at will. The frames 24 on each side of the vessel are connected by bars 26, said bars being pivoted to the said frames. To one bar 26 on each side of the structure are fixedly attached downwardly extending arms 27, to the lower ends of which are pivoted at 28 horizontally disposed levers 29, which extend into a cage 30,

- that is suspended from bars 31, the latter running in parallel relation to the front and rear of the frame of the vessel and being rigidly attached to the glider frame 13. Within the cage 30, which is rigidly mounted upon the bars 31, is arranged the operator's seat 32, the operator being able to slide along the entire length of the cage and being protected from drafts by wedge-shaped structures 33, which are attached to the cage in front and rear thereof. It is to be observed that the seat 32 may accommodate more than one person, for instance one behind the other. Attention is called to the fact that the greater the weight on the operator's seat, the greater will be the stability of the machine. The levers 29 on each side of the vessel are provided with a handle 34 in the form of a bar, that extends horizontally throughout the length of the cage 30 to enable the operator to actuate either set of levers 29, in whatever position the operator be upon the seat. To hold the arms 27 in any position, each side of the vessel frame carries a horizontal inwardly extending projection 35, having longitudinal corrugations 36 upon its upper face, with which are adapted to coöperate teeth 37 upon the levers 29 to prevent a shifting of the levers 29 in transverse directions.
- To guide the vessel in the vertical plane, steering planes 38 are fastened to a transverse spindle 39, that is oscillatably mounted in extensions 40 of the frame of the vessel. To the spindle is attached an upwardly extending arm 41, to which is pivoted at 42 a steering rod 43, that extends into the cage 30 and runs throughout the length thereof for the same reason as the handles 34 of the levers 29 run in a similar manner throughout the length of said cage. Inasmuch as the elevating planes 38 are disposed at a substantial distance from each other, they serve at the same time as lateral balancing means. In front of the frames 24 is mounted upon each side of the vessel frame a wedge-shaped structure 44 to protect the said frames from the wind. The planes 23 may be curved, as shown in Fig. 4 of the drawings, or they may be flat as shown in the remaining figures.

The operation of this device is as follows: It seems it is necessary to describe only the function and operation of the planes 23 in coöperation with the propellers 20, since the operations of the other elements of the vessel are well known. In starting the ascent of the vessel, all frames 24 are shifted into the positions in which they are shown in Fig. 3 of the drawings on the left side of the vessel frame. The engine is then started and the steering planes 38 set to cause the vessel to ascend. The propellers force the air toward the planes 23, by which it is deflected and caused to move toward the rear of the

aerial vessel, thereby causing the same to move in the direction of the arrow shown in Fig. 2 of the drawings. The speed of the vessel may be changed by varying the exposed surfaces of the planes 23 relative to the propellers, more particularly the more the said planes are shifted to closing positions, the greater the speed of the vessel, and the more they are shifted to opening positions, that is to say the nearer they are brought into the position shown on the right side of the device in Fig. 3 of the drawings, the slower the speed of the device. From this it appears that in order to change the speed of the vessel, it is not necessary to change the speed of the engine thereof. The disks 22 serve to prevent the setting up of counteracting air currents by the two propellers of the device. In order to produce a change of direction in the course of the aeroplane in a horizontal plane, one or the other set of planes 23 is shifted in the proper direction as it is intended to cause the vessel to move to the right or to the left. It is to be noted that, since the propellers rotate in planes parallel to the direction of travel of the vessel, obviously they offer the least resistance to the air, and increase thus the speed of the device. To steer the aeroplane into a higher or a lower plane, the planes 38 are made use of in the usual manner, or the operator may change his position upon the cage 30.

It is to be observed that, while herein an aeroplane of a special construction has been described, the improvement may be applied to others just as well, the invention lying mainly in the provision of a plurality of shiftable planes, which in coöperation with the propellers of the device, are adapted to predetermine the course of the vessel and at the same time to vary its speed at will without changing the speed of the propellers.

It is to be noted that the poiser or aeroplane frames 13 and 14 are wholly disposed within the frame 10 of the apparatus. A very strong and practically indestructible structure is thus obtained.

It is to be observed that the aeroplane herein described does not need any special stabilizing means, the device being stable for the reason that the entire weight is suspended from the glider frames 13 and 14, and furthermore because the propellers force the air laterally in both directions. Inasmuch, as above described, the entire weight of the vessel is suspended from the glider frames 13 and 14, the aeroplane will not turn upside-down in case its machine comes to a full stop in midair, on the contrary the machine will slowly descend in its upright position. The aeroplane can be stopped immediately or it can be caused to move backward, no matter whether on land or in the air, by properly setting the two sets of

planes 23. The driving mechanism herein described may be applied to vessels other than aeroplanes.

What I claim is:—

- 5 1. In an aerial vessel, the combination with a main frame, a glider frames upon the top thereof, a plurality of vertically disposed planes oscillatably mounted upon each longitudinal side thereof and below said 65
10 glider frames, and a propeller associated with each set of planes, each propeller being located in close proximity to its corresponding set of planes and causing thus an unobstructed passage of air to its planes.
- 15 2. In an aerial vessel, the combination with a main frame, of glider frames upon the top thereof, a plurality of vertically disposed planes oscillatably mounted upon each longitudinal side thereof and below said 70
20 glider frames, a propeller associated with each set of planes, each propeller being located in close proximity to its corresponding set of planes and causing thus an unobstructed passage of air to its planes, and means for shifting said planes around their pivots to 75
25 vary their exposed surfaces relative to said propellers.
3. In an aerial vessel, the combination with a main frame, of glider frames upon the top thereof, a plurality of vertically disposed planes oscillatably mounted upon each longitudinal side thereof and below said 80
30 glider frames, a propeller associated with each set of planes, each propeller being located in close proximity to its corresponding set of planes and causing thus an unobstructed passage of air to its planes, and means for 85
35 independently shifting each set of planes around their pivots to vary their exposed surfaces relative to said propellers.
4. In an aerial vessel, the combination with a main frame, of glider frames upon the top thereof, a plurality of vertically disposed planes oscillatably mounted upon each longitudinal side thereof and below said 90
45 glider frames, a propeller associated with each set of planes, each propeller being located in close proximity to its corresponding set of planes and causing thus an unobstructed passage of air to its planes, and means for 95
50 independently shifting each set of planes around their pivots to vary their exposed surfaces relative to said propellers.
5. In an aerial vessel, the combination with a main frame, of glider frames upon the top thereof, a plurality of vertically disposed planes oscillatably mounted upon each longitudinal side thereof and below said 100
55 glider frames, a propeller associated with each set of planes, each propeller being located in close proximity to its corresponding set of planes and causing thus an unobstructed passage of air to its planes, and means for simultaneously shifting each set of said 105
60 planes around their pivots to vary their exposed surfaces relative to said propellers.

Signed at New York, in the county of New York, and State of New York, this 12th day of March, A. D. 1914.
